APPARATUS FOR WEAR INDICATING AND
LOGGING WHILE DRILLINGEverett A. Johnson, Park Ridge, Ill., assignor to
Standard Oil Company, Chicago, Ill., a corpora-
tion of Indiana

Application February 27, 1947, Serial No. 731,242

4 Claims. (Cl. 255—1)

1

This invention relates to method and apparatus for transmitting information or indications of operating conditions from an inaccessible point, for example from a bore hole to the surface of the earth. More particularly, the invention pertains to method and apparatus for detecting well tool wear.

This invention has particular utility in connection with logging-while-drilling wells. During the drilling of wells it is desirable to determine at least the approximate nature or character of the geological strata traversed and the invention includes means whereby the conductivity of strata traversed by a drill hole may be measured or indicated during the drilling operation. It also includes means for continuously measuring the natural potential in the region of the well.

In the rotary drilling of wells a drill bit is advanced through the successive formations by the rotation of the drill stem, a drilling fluid being circulated into and out of the well for the purpose of removing the drill cuttings, lubricating and cooling the bit, etc. Frequently, the drill fluid is repeatedly used in a substantially closed circuit and is replenished only to the extent that it is absorbed by the penetrated formations. The formation through which the well is passed is subjected to the downward pressure and to the cutting and grinding action of a revolving metal bit. The hardness and density of the strata traversed determine the resistance to penetration and displacement and, in turn, determine the length of time a bit will be effective.

Two general types of bits are known in the art, one being the drag bit which is particularly adapted to loosely-cemented sands, shales, and clays, and the other being the rock roller or cone bit which depends upon a crushing and chipping action. These bits are well known and widely used in oil field drilling. The drag bit wears on both the bottom and the side cutting edges; whereas the rock bit failure frequently occurs at the bearings upon which the cones or rollers are mounted.

In operation the cutting bit usually is revolved by a hollow drill stem and at the surface means are provided for rotating the drill stem and for supplying a drill fluid to the hollow drill stem. The drill fluid passes downwardly through the drill stem, flows out into the well through the bit, sweeps under the bit, and suspends the drill cuttings therein for transfer to the surface. When the fluid laden with drill cuttings reaches the surface, it is introduced into a separating ditch or trough wherein the relatively coarse ma-

2

terials are settled out. Alternatively the drill mud can be passed over a shaker screen which retains the well cuttings. In any event, the drilling fluid or mud from which the cuttings have been removed is introduced into an accumulation trough or sump from which it is pumped back into the well. A modification of the above operation is that which is termed "reverse circulation." In such a system the drill fluids are pumped downwardly outside of the drill stem and are returned to the surface through the drill stem.

If the drill bit is permitted to become dull as a result of wear or failure, the drilling rate and/or the well diameter will be reduced. Eventually the drilling rate will be reduced until further drilling with the same bit would not be economical. In passing from a relatively soft formation the drilling rate will also be reduced and it has not always been possible to distinguish between the possible causes for reduction in drilling rate. Consequently, drill bits have been pulled prematurely. It is also possible that the nature of the formation through which the bit is passing is such that the side cutting edges of the drill bit may also become worn without being detected and the hole will be off gauge. Consequently, the problem becomes one of detecting the failure or extent and character of the wear of a drill bit.

Drill bits are available at relatively high costs which are capable of drilling substantial distances without being replaced; however, since the bit is relatively inaccessible, it has not heretofore been possible to determine with sufficient accuracy the degree and character of the wear. This is important because in order to replace a drill bit it is necessary to pull the entire drill string, which is a time-consuming and expensive operation. It is evident, therefore, that it is highly desirable to know the condition of the drill bit if optimum drilling conditions are to be maintained with a minimum amount of drill stem pulling.

Heretofore various means have been proposed for the indication of drill bit wear. One such means includes an insert of detectable solid marker material a predetermined distance from the edge of the cutting surfaces. Thus, when the selected extent of wear has occurred, the indicator substance is released into the well stream and is carried to the surface where it is detected by suitable apparatus. For example, it has been proposed that a radioactive material be released into the well stream and detected at the surface by means of highly-specialized equipment. It

has also been proposed to imbed a container of highly-colored material in the structure so that the colored material would be released into the mud by the penetration of the guide shoe. The detection of colored particles requires constant and diligent search, and it has been the experience of operators that their presence may escape detection. Furthermore substances such as dyes are absorbed by the opaque drill mud to such an extent that they cannot be detected with considerable accuracy and are considered to be unsatisfactory for the intended purpose.

It is, therefore, an object of my invention to provide a simple method and means for transmitting information or indications of certain conditions of apparatus within a well bore. It is a further object to provide a method and means for positively indicating, at the surface, the extent and character of wear of well tools within the well bore. Another object is to provide a well logging system which automatically indicates a predetermined extent of bit wear. A further object is to provide a logging-while-drilling system wherein an electrical log is obtained and the condition of the bit is indicated electrically. These and other objects will become apparent as the description of my invention proceeds with reference to the drawings wherein:

Figures 1 and 2 are diagrammatic representations of drilling assemblies employing my indicator electrode means;

Figure 3 is a schematic showing of a circuit adapted for logging-while-drilling and for indicating bit wear; and

Figure 4 is a diagrammatic representation of a drilling assembly for use with the circuit shown in Figure 3.

Referring to Figures 1, 2 and 4, the apparatus includes a drill bit 10, having bottom cutting edges 11, and drill stem 12. The bit 10 may be provided with one or more cavities 13 which extend inwardly from a wearing surface. An insulated electrode 14 is disposed within the cavity 13 and wear plug or shield 15 normally protects the electrode 14 within the cavity 13 to a depth corresponding to the allowable wear. Thus, during the drilling operation the metal of the well tool and the shield 15 wear away, exposing the electrode 14 when a predetermined amount of wear has occurred. A threaded plug of insulating material can be used to shield the electrode 14 but other convenient plugging means may be substituted. The electrodes may be of any desired area or configuration so long as an electrical signal is transmitted to the wear indicating or well logging circuit.

In Figure 1 the drill bit 10 is provided with an insulated electrode 14 within cavity 13 enclosed by shield 15. The electrode 14 is connected to the electrically conducting drill stem 12 by conductor 22 at 23 and insulator 16 is disposed between the drill 10 and drill stem 12. A battery 17 and an electrical measuring instrument such as a galvanometer 18 in series with electrode 21 and drill stem 12 are provided at the surface. Normally there is no flow of current between the electrode 21 and the drill bit 10 but when the shield 15 is removed by the wearing of the drill bit, the electrode 14 is exposed and the circuit including indicating electrode 14 and the ground electrode 21 is completed. Upon the completion of this circuit there is an indication at the surface by galvanometer 18 that the predetermined extent of wear has occurred.

Another embodiment of the invention is illustrated in Figure 2 wherein the indicating circuit includes the shielded electrode 14, the power source 17 and an electrical measuring instrument 18. In addition the conductors 20 and 22 and electrode 14 comprise one portion of the circuit and the conductor 19, drill stem 12 and bit 10 form another portion of the circuit. As before, when the shield 15 is removed, the circuit is completed between the then exposed electrode 14 and the drill bit 10 by the well fluid or formation thereby giving an indication of the predetermined extent of wear.

Thus, each of the embodiments illustrated in Figures 1 and 2 comprises a bit 10 provided with one or more insulated electrodes 14 which are electrically shielded by plug 15 and which are connected by means of insulated conductors with an electrical measuring instrument at the surface which indicates that a particular electrode has become exposed.

If desired, two or more indicating electrodes may be used on different portions of the well tool, guide shoe, and the like, so that it will be possible to determine not only the extent but also the character of the wear, failure, or penetration. For example, if different indicating means are used on the bottom and side cutting blades of a drag bit, it is readily determinable whether continued drilling would result in decreasing drilling rate or in reducing hole diameter. It is also contemplated that my indicating means can be employed on any type of well tool or apparatus including drill pipe protectors, pins in roller bits, casing collars, reamers, and the like to indicate the failure, extent and character of wear, or penetration.

With reference to Figure 3 I have provided a combination logging and bit wear indicating circuit, which circuit is so integrated that a minimum of apparatus is required. The logging circuit comprises an A. C. portion for measuring the earth resistivity, which A. C. is rectified to a pulsating D. C. current supplied to a D. C. recorder. The portion of the circuit for indicating bit wear is a D. C. circuit which is connected in parallel to the D. C. portion of the logging circuit. More specifically, alternating current generator 25 having a constant output is connected to a coupling transformer 29 by leads 27 and 28. Logging electrodes 31 and 32 are connected through their respective leads 31a and 32a to the coupling transformer whereby a fixed alternating potential is supplied across the electrodes. Electrode 32 is located at the base of the well being logged and may be, for example, the drill bit, and electrode 31 is an electrode located at the surface or in the well some distance from the first electrode 32. Variations in the resistivity of the earth surrounding electrode 31 or of the well fluids when both electrodes are in the well will cause variations in the current flowing in lead 32a, which current variations are converted into a variable potential across a fixed resistance 34 in lead 31a. This varying A. C. potential is amplified in a suitable amplifier 35 and rectified in a full wave rectifier 36. The pulsating D. C. output of the full wave rectifier is then fed through lead 27 on one hand and leads 51 and 28 on the other to the recording portion of the logging circuit. It should be particularly noted that by converting the variable potential across the logging electrodes into a D. C. potential, leads 27 and 28 which, as pointed out above are carrying A. C. potential to the logging electrodes, may be used without inter-

ference. Blocking condensers 26 are inserted in leads 27 and 28 to prevent the D. C. from reaching generator 25, and blocking condenser 30 is inserted in the circuit similarly to protect the coupling transformer 29. Choke coils 37 in leads 27 and 28 similarly prevent A. C. from reaching the rectifier 36.

The recording portion in the logging circuit may include a customary D. C. indicator 41 such as an oscillograph galvanometer and a potential divider comprising a source of potential such as a battery 40 across which is a variable resistance 42. The potential divider serves the purpose of permitting the adjustment of the zero point of the recorder. Choke coils 39 protect the D. C. recorder from the A. C. current. A recorder of this type will record the pulsating D. C. output of the full wave rectifier 36, in the circuit as described, as a variation in amplitude with depth or alternatively with time.

Looking now to the circuit for indicating bit wear, this comprises a pair of electrodes 43 and 44 with suitable corresponding leads 43a and 44a with lead 51 having resistance 52 therein bridging these electrodes. A source of potential, such as battery 53 in lead 44a, permits the establishment of a fixed D. C. potential across the resistance 52, which fixed potential is added or subtracted with respect to the pulsating D. C. output of the full wave rectifier 36. This potential is established only when there has been sufficient wear of shield 15 to permit an electrical path between electrodes 43 and 44. The imposition of the fixed D. C. potential on the D. C. portion of the logging circuit will be reflected in the D. C. recorder by a fixed increase or decrease, as the case may be, in the magnitude of the recorded current. Thus, an indication that wear has occurred will be obtained without interfering with the recording of the pulsating D. C. indicative of the logging measurements being made.

A measuring sheave or pulley 45 is connected through suitable mechanical connections, represented by the shaft 46 with Selsyn generator 50, the function of which is to maintain synchronism between the pulley 45 and the recording medium 47. The recording medium is driven by Selsyn motor 48 which is kept in synchronism with generator 50 by conductors 49.

A large number of methods are available for following the downward movement of the drill bit 10, but a preferred method is a wire line attached at its lower end to a traveling block which supports the drill string 12 and passed over a pulley 45 located substantially directly above the traveling block and then wound upon a drum which is provided with a spring having a strength sufficient to keep the wire line in slight tension regardless of the position of traveling block. Obviously, the pulley 45 rotates in a manner dependent upon the vertical movement of the traveling block and hence of the entire drill string 12 and bit 10. I have chosen in this instance to utilize pulley 45 as the means for providing depth indications and for this purpose the Selsyn generator 50 is illustrated connected to the pulley 45. Any rotation of pulley 45 is therefore transmitted by means of generator 50 and conductors 49 to the corresponding Selsyn motor 48, which is preferably located a short distance away from the drilling rig, and which is utilized to drive the recording medium 47.

Figure 4 illustrates a drill bit and shielded electrode assembly adapted for use with the combination logging and indicating circuit schematically illustrated in Figure 3. In this embodiment

the ground electrode 31 and the drill bit 10 correspond to the logging electrode system 31 and 32 of Figure 3. Likewise, the shielded electrodes 14 and 44 correspond to the indicating electrode system 43-44. Therefore, if the leads 31a, 32a, 43a, and 44a of Figure 3 were connected as illustrated in Figure 4, the apparatus would be adapted to logging-while-drilling and in addition would provide means for obtaining an indication of the allowable wear of the drill bit 10. The logging circuit would then operate on an A. C. potential and the drill bit wear indicating circuit on a D. C. potential. It is also contemplated that more than one electrode can be connected to each conductor in any one of the embodiments herein described. In any event, the logging-while-drilling data are not adversely affected by the indicating circuit but a single trace can be obtained to show a conventional electrical log and the predetermined extent of wear of the drill bit.

From the above, it will be apparent that I have attained the objects of my invention and have provided a novel method and means which is useful for indicating wear of well tools and which means may be integrated with a logging-while-drilling system.

Although my invention has been described with reference to particular embodiments thereof, it should be understood that they are for illustration only. For example, it is contemplated that my method and apparatus, which have been described with particular reference to detecting the disintegration of an element, will be useful in transmitting information from any inaccessible apparatus, particularly where there is an electrical conducting fluid in the region of the inaccessible element. Therefore, the invention is not limited to the illustrated embodiment but is defined by the appended claims.

I claim:

1. A drilling assembly comprising a hollow drill stem of electrically-conducting material, a coupling of electrically-insulating material fixed to the lower end of said drill stem, an electrically-conducting drill bit carried by said coupling, a recess in said drill bit communicating with said hollow drill stem through a channel in said bit, said channel accommodating an insulated electrical conductor electrically connected to the lower end of said drill stem above said coupling, an electrode in said recess connected to said electrical conductor in said channel, a plug of insulating material closing the said recess and electrically shielding the said electrode, and a surface circuit including a battery, an electrical measuring instrument, and a ground electrode in series with said drill stem, electrical conductor, and shielded electrode, whereby the disintegration of the shielding plug during drilling exposes the drill bit electrode within said recess to complete the electrical circuit so as to give a surface indication that a given extent of drill bit wear has occurred.

2. An apparatus for logging bore holes and for indicating bit wear comprising an alternating current generator having a constant output, a coupling transformer connected to said output, a pair of vertically spaced logging electrodes connected to the coupling transformer whereby a fixed alternating potential is supplied across the logging electrodes, one of said electrodes being positioned within a bore hole, a fixed resistance in the circuit between the logging electrode within the bore hole and said coupling transformer, an amplifier across said fixed resistance, a full

wave rectifier, leads from said amplifier to said rectifier, conductor means for feeding the pulsating direct current output of the full wave rectifier to a recording portion of the logging circuit, said recording portion of the logging circuit including a direct current indicator and a potential divider, a choke coil for protecting the D. C. recorder from A. C. current, a pair of indicating electrodes, a pair of electrical leads connected respectively to each of said indicating electrodes, a fixed resistance bridging said leads, a source of potential in series with said indicating electrodes and bridging resistance, one of said leads being fixed to said full wave rectifier and the other of said leads being connected to said coupling transformer whereby said source of potential becomes effective when the circuit is closed between the indicating electrodes, and an indication of the extent of wear is obtained on the D. C. recorder without interfering with the recording of the pulsating D. C. current which is indicative of the resistivity logging measurements in the logging circuit.

3. An apparatus including a drill bit having cutting edges, a recess in one of said edges, a passage extending from within said bit and in communication with said recess, an insulated conduc-

tor extending within said passage and having a terminal exposed within said recess, a separable plug of electrical insulating material electrically sealing the said recess, and an electrical circuit including a current source, a current responsive indicator and said conductor in series, whereby wearing away of the cutting edge to an extent such as to remove the plug from the recess exposes the terminal of the conductor for closing the electrical circuit and producing a signal on said indicator.

4. The apparatus of claim 3 wherein the current-responsive indicator is a galvanometer.
